ATTORNEY

UNITED STATES PATENT OFFICE.

JOHN M. MELE, OF EAST HAVEN, CONNECTICUT.

SIGNAL DEVICE.

Application filed August 30, 1926. Serial No. 132,476.

This invention relates to a new and improved signal device, especially designed to be used in connection with a motor vehicle.

It is the object of this invention, among 5 other things, to provide a device of this character which will display the ordinary rear light, as is required by statute in practically all jurisdictions, and also a stop or other signal which may be operated automatically 10 with the movement of the brake mechanism, and to accomplish these desirable results with mechanism that will be entirely enclosed and thus protected from external injury and will in its details and 15 operation contain many decided advantages over signal devices of this character heretofore made.

The improvements in the details and arrangement of parts will be apparent from 20 an inspection of the accompanying drawings, in connection with the description hereinafter contained and wherein a preferred embodiment of the invention is disclosed for the purpose of imparting an understanding 25 of the same.

Referring to the drawings, wherein like numerals of reference designate like parts in the several figures;

Figure 1 is a side elevation of a motor 30 vehicle having my improved mechanism connected thereto;

Figure 2 is a front elevation of my signal device with a license plate attached thereto;

Figure 3 is a sectional view thereof;

Figure 4 is a transverse sectional view, the 35 parts in section being taken generally upon line 4-4 of Figure 3; and

Figure 5 is a perspective view of the display drum.

Referring now more particularly to the drawings, 10 designates the cylinder which is preferably made of nonbreakable glass or the like and closed at its opposite ends by caps 11 and 12, between which and the end 45 of the cylinder 10 are the washers 13. These parts are held together as a unit by the bolts 14, which pass through the caps and provided with nuts as is usual.

By thus enclosing the mechanism a structure 50 is provided wherein it may be seen from the exterior and at the same time is guarded against external injury as well as kept free from sand, dirt, snow, ice, etc., that accumulates upon a motor vehicle.

Projecting into the cylinder 10 is a lamp 55 socket 15 of usual form, having an incan-

descent lamp 16 at the inner end and a plug 17 at the outer end, from which leads a cord 18, through which is conducted a current of electricity.

Within the cylinder is a display drum 19, which is semi-circular in form, having heads 20 and 21 at its opposite ends, the former having an opening 22, through which passes the socket 15 and in the latter is an opening 23, to receive the journal screw 24 having a nut 25 thereon. This display drum 19 rotates about an axis coincident with that of the cylinder 10, power for which is derived from the spring 26 in one direction 60 and in the opposite direction from the brake mechanism 27 through the cord 28 connected with the head 21, and brake mechanism 27, a spring 29 being preferably interposed therebetween. Movement of the brake 70 mechanism 27 pulls the cord 28 and through it the display drum 19 is moved about its axis until it assumes the position shown by broken lines in Figure 4, at which time one edge of each of the heads is brought into 80 contact with one of the bolts 14, thus forming a stop therefor.

The cord 28 is surrounded for a portion of its length by a flexible tubing 30, the inner end of which is threaded through the offset portion 31 upon the head 21.

The end of the flexible tubing 30 is threaded into the offset portion and thus forms an inseparable connection therewith.

Through the wall of the display drum 19 are two openings, 32 and 33, the former being a single opening elongated in shape and the latter formed in the shape of figures or letters, as shown in Figure 5, forming the word "Stop".

Fastened to the inside of the display drum opposite and covering the opening 32 is a transparent plate 34, either of glass, celluloid or the like, preferably red in color and opposite the opening 33 are two plates 35 and 36, the plate 35 being preferably made of white glass, celluloid or the like, and the plate 36 of the same material, but preferably green.

The numeral 37 designates the bracket, the lower portion 38 of which is preferably flat and having elongated slots 39 therein, through which project screws 40 or the like, by means of which the license plate 41 may be attached thereto. The upper portion of this bracket is curved at 42, and extends partly around the rear side of the cylinder 105 110

10, being held in position by the caps 11 and 12.

If it is desired, the inner face of the curved portion 42 may be painted white or the like, to form a reflector, or if desired a piece of white paper, cloth, or the like, may be inserted for the same purpose.

When the motor is being operated and no pressure is being applied to the brake mechanism, the several parts of my signal device are in the relative positions shown in Figure 4, with the opening 32 in the display drum displayed through the rear of the cylinder 10 and the openings 33 opposite the curved portion 42. When so positioned the red rear light is displayed through the transparent plate 34. As the brake mechanism is actuated display drum 19 is rotated about its axis and the openings 33 are moved in position so that the word "Stop" may be seen through the rear of the cylinder instead of the transparent plate 34, as above described. This action is against the tension of the spring 26 which upon release of the brake mechanism returns the display drum 19 to its former above-described position. If perchance the extent of movement of the brake mechanism 27 exceeds the length of possible movement of the display drum 19, such excess is absorbed by the spring 29. As the display drum 19 is only parti-circular and the shell thereof is above its axis, the light from the lamp 16 is projected downward through the cylinder 10 onto the face of the license plate 41, which light is not shut off even though the display drum 19 is moved about its axis to display the word "Stop", as above described.

Within the scope of the appended claims minor changes may be made within my invention, aside from those herein suggested.

What I claim as new and desire to secure by Letters Patent, is:—

1. In mechanism of the character described; a cylinder of glass or the like; a cap closure for both ends thereof; one or more bolts extending through the caps and the chamber within the cylinder for securing the cylinder and caps together as a unit; a display drum within the cylinder, parti-circular in form, and movably mounted therein, and having plural openings therethrough, one of such openings being formed in the shape of letters; a transparent plate connected with the display drum opposite each of said openings; and a flexible connection between the display drum and the brake mechanism of the motor vehicle, said bolts being so positioned as to form stops to limit the movement of the drum.

2. In mechanism of the character described; a cylinder of glass or the like; a cap or closure for both ends thereof having side walls; means as one or more bolts, for securing the caps and cylinder together as

a unit; and a bracket having a curved portion which partly encircles the cylinder upon the outside thereof and is rigidly connected therewith by means of said caps but without rivets or the like, and having a substantially straight portion adapted to support a license plate, each end of the said curved portion being between the outside of the cylinder and the walls of the cap.

3. In mechanism of the character described; a cylinder of glass or the like; a cap closure for both ends thereof; one or more bolts extending through the caps and the chamber within the cylinder for securing the cylinder and caps together as a unit; a display drum within the cylinder, parti-circular in form, and movably mounted therein, and having plural openings therethrough, one of such openings being formed in the shape of letters; a transparent plate connected with the display drum opposite one of said openings; transparent plates of different colors connected with the display drum opposite another of said openings; and a flexible connection between the display drum and brake mechanism of the motor vehicle, said bolts being so positioned as to form stops to limit the movement of the drum.

4. In mechanism of the character described; a cylinder of glass or the like; a cap or closure at both ends thereof, one of said caps having an offset portion; means as one or more bolts within the cylinder for securing the caps and cylinder together as a unit; a display drum movably mounted within the cylinder; a flexible connection between the display drum and the brake mechanism of the motor vehicle; and a member enclosing the flexible connection that projects into the said offset portion upon one of the caps, said bolts being so positioned as to form stops to limit the movement of the drum.

5. In mechanism of the character described; a cylinder of glass or the like; a cap or closure for both ends thereof; means as one or more bolts within the cylinder for securing the caps and cylinder together as a unit; a display drum within the cylinder, parti-circular in form, and movably mounted therein, and having plural openings therethrough; a coil spring connected at one end with one of said caps and at the other end with a part of said drum for imparting movement thereto in one direction; and a flexible connection for moving the drum in the opposite direction, which projects through one of the caps and is connected with the display drum, said bolts being so positioned as to form stops to limit the movement of the drum.

In testimony whereof, I have hereunto affixed my signature.

JOHN M. MELE.
